UNITED STATES PATENT OFFICE.

JOSEPH MOSELEY AND BENJAMIN BLUNDSTONE, OF MANCHESTER, COUNTY
OF LANCASTER, ENGLAND.

ENGINE-PACKING.

SPECIFICATION forming part of Letters Patent No. 425,042, dated April 8, 1890.

Application filed August 14, 1889. Serial No. 320,732. (No model.) Patented in England February 28, 1889, No. 3,567, and March 12, 1889, No. 4,276.

To all whom it may concern:

Be it known that we, JOSEPH MOSELEY and BENJAMIN BLUNDSTONE, citizens of the United Kingdom of Great Britain and Ireland, and residents of the city of Manchester, in the county of Lancaster, England, have invented certain new and useful Improvements in Engine-Packings, (for which we have obtained Letters Patent in Great Britain No. 3,567, dated February 28, 1889, and No. 4,276, dated March 12, 1889,) of which the following is a specification.

This invention relates to engine-packings; and these improvements consist in the combination and arrangement in the packing of a metallic gauze element in such a manner as to preserve the flexibility and pliability of the packing, while at the same time the firmness and durability due to the metallic element are secured to the fullest extent.

In order that our invention may be more readily understood, we will proceed to describe it with reference to the accompanying drawings, in which—

Figure 1 represents a plain sheet of metallic gauze; Fig. 2, a similar sheet in preparation for use in the construction of the packing, and Figs. 3, 4, 5, 6, 7, and 8 various forms of packing constructed according to this invention.

In each of the figures in which the parts are represented, *a* is the metallic gauze. *b* is the outer layer or covering of the packing. *c* is the layer or layers of fabric used in combination with the metallic gauze, and *d* is a strip or core of india-rubber or similar or suitable material.

The metallic gauze is first prepared by grooving, corrugating, or indenting it by rollers or other suitable means, and by preference parallel either with the warp or with the weft. The corrugated groove or indented sheet of metallic gauze is then cut diagonally or "in bias," as indicated in Fig. 2, into strips of such a width as may be required. These strips are used in the manufacture of the packing in addition to or in substitution for some of the layers or plies of asbestos or other suitable fabric ordinarily employed.

In the packing represented in Fig. 3 a strip of the corrugated, indented, or grooved metallic gauze cut from the sheet, as hereinbefore described, is doubled with a strip of asbestos or other similar and suitable fabric, and the doubled material is then folded and refolded until the desired dimension is obtained. The packing is then enveloped in a covering of a fabric *b*, such as is ordinarily used for the purpose in the manufacture of known packings.

In the packing represented in Fig. 4 alternate strips of suitable textile fabric and of the prepared metallic gauze are cemented together in alternate layers. The strips thus secured together may be surrounded on three sides by a covering *b* of suitable textile material, so as to leave exposed the alternate edges of the metallic gauze and textile material along one edge. As shown in the drawings, a strip of india-rubber *d* is added to the composite strips before the covering *b* is cemented on.

In constructing the packing represented in Fig. 5 we may first double or cement together a strip of the prepared metallic gauze and a similar strip of textile fabric and roll them together, as represented in Fig. 8. This roll is then by suitable dies or other known means compressed into a square or prismatic form, and the packing is finally completed, as hereinbefore described with reference to Fig. 4. In this form of packing, Fig. 5, the prepared metallic gauze forms the outside of the roll, and when therefore the packing is finished the metallic gauze is exposed on the wearing, surface, as indicated at *a* in the figure.

The packing illustrated by Fig. 6 resembles that shown in Fig. 3, except that a strip of india-rubber *d* is included thereon.

The circular packings, Figs. 7 and 8, are made by double strips of the prepared metallic gauze and of suitable textile fabric rolled together. As indicated in Fig. 7, a core of india-rubber is included in the packing.

The prepared metallic gauze and the textile fabric may, when required, be "doubled" or secured together by cement or by other suitable means in a similar manner to that at

present adopted for securing the different layers together in similar packings of ordinary construction.

It will be obvious that since the metallic

- 5 gauze is so prepared that the corrugations, indentations, and grooves are diagonal in the strips which are employed in the construction they will also be diagonal (or spiral, if rolled) in the finished packing.
- 10 It is preferred to make the corrugations, grooves, and indentations comparatively small and close together. No precise dimensions need to be observed; but if the corrugations are about one-half millimeter deep and
- 15 two millimeters apart for ordinary packings a very good result will be obtained. Other greater or less dimensions may be used when desired, or for larger or smaller packings than the average.
- 20 The indentations made in the metallic gauze may be so acute as to nearly or completely sever the gauze into tapes or ribbons. In this case we interrupt the acute indentations at intervals so that the severed or
- 25 nearly severed portions may be held together at the points where the indentations are interrupted. A piece of metallic gauze prepared with these acute indentations is represented in Fig. 9, where the vertical broken
- 30 lines represent the interrupted indentations and the diagonals represent the lines along which the acutely-indented gauze is cut into strips to be used in the manufacture of the packing. The interruptions between the
- 35 acute indentations are at such frequent intervals that there shall at least be one such interruption in each line of indentation between each diagonal cut. When this precaution is taken, the strip severed from the sheet
- 40 by any diagonal cut will be held together by the parts which are not acutely indented or incised.

The corrugation of the metallic gauze on the line of the warp or weft and the diagonal

cutting give to the packing when completed 45 a high degree of elasticity and pliability and great durability.

The forms of the packings illustrated by the accompanying drawings are well known, and we therefore do not claim them apart 50 from the arrangement therein and the hereinbefore-described combination therewith of the prepared metallic gauze. The types illustrated are those of the packings at present more generally in use, and they have been selected for illustration for this reason only; but our invention may be applied to other forms and types of packings with equal advantage, and we desire it to be therefore understood that we do not limit our invention 60 to the types and forms of packings illustrated by the drawings.

Having now particularly described and ascertained the nature of our said invention and in what manner the same is to be performed, we declare that what we claim is—

1. In engine-packings, the combination and arrangement of a layer or layers of textile fabric with a layer or layers of metallic gauze prepared by being corrugated, indented, 70 or grooved, and cut diagonally into strips, substantially as hereinbefore described.
2. In engine-packings, a layer or layers, ply or plies, of metallic gauze prepared by being corrugated, indented, or grooved, and arranged in the packing in such a manner that the corrugations, indentations, and grooves are in a spiral or diagonal direction, substantially as hereinbefore described.

In testimony that we claim the foregoing 80 as our invention we have signed our names in presence of two witnesses.

JOSEPH MOSELEY.
BENJAMIN BLUNDSTONE.
